HANGER BAR

Joseph P. Franz, Mount Clemens, Mich.

Application December 21, 1950, Serial No. 202,080

3 Claims. (Cl. 211—123)

1

This invention relates to a hanger bar having anchoring studs projectable into penetrating engagement with adjacent supports by a force induced by an explosive charge detonation.

An object of this invention is to provide a hanger bar having anchoring studs projectable in response to force induced by an explosive charge detonation, which is particularly adapted for quick and easy attachment between a pair of spaced supports.

Another object of this invention is to provide a hanger bar having anchoring studs projectable in response to force induced by an explosive charge detonation, which is particularly adapted for use in rewiring buildings, wherein it is essential to provide a firm, durable and permanent mounting for electrical junction boxes and the like.

A further object of this invention is to provide a hanger bar having anchoring studs projectable in response to force induced by an explosive charge detonation which cannot be accidentally discharged and is safe and simple to use.

A still further object of this invention is to provide a hanger bar having anchoring studs projectable in response to force induced by an explosive charge detonation which is provided with a detachable reinforcing sleeve to minimize the possibility of the hollow tube rupturing when the charge contained therein is exploded.

A still further object of this invention is to provide a hanger bar having anchoring studs projectable in response to force induced by an explosive charge detonation for attachment between a pair of spaced supports, which is relatively simple in structure and cheap to manufacture.

The above and still further objects and advantages of the present invention will become apparent upon consideration of the following detailed description, when taken in conjunction with the accompanying drawings, wherein:

Figure 1 is a side elevational view of a hanger bar constructed according to the present invention, shown supported between a pair of spaced supports;

Figure 2 is a side elevational view of the hanger bar of the present invention shown assembled with the reinforcing sleeve;

Figure 3 is an end elevational view of the assembly of the hanger bar and reinforcing sleeve taken from the left of Figure 2;

Figure 4 is a sectional view taken along the line 4—4 of Figure 3; and

Figure 5 is a sectional view taken along the line 5—5 of Figure 2.

Referring now more particularly to the drawings, wherein like reference numerals have been used throughout the several views to designate like parts, there is shown the hanger bar 10 which

2

is adapted to be attached between a pair of spaced supports 11 and 12, such as joists or trusses in a building.

The hanger bar includes an open-ended, hollow tube 15 which is provided with an axial firing bore 16.

Disposed within the tube 15 intermediate the ends thereof is an explosive charge 17 which substantially bridges the axial bore 16 and is supported therein.

Arranged in back-to-back, spaced relation with respect to each other are a pair of projectile-like studs 18 and 19 which are normally arranged in the medial portion of the tube on opposite sides of the charge 17 and spaced therefrom. Each of the studs 18 and 19 includes a cylindrical body 20 shaped complementary to and snugly fitting in the firing bore 16, and a support-engaging prong 21 projecting from the outer end thereof and facing toward the adjacent open end of the tube 15. Each of the studs 18 and 19 is adapted to be driven toward the adjacent open end of the tube 15 and into engagement with the adjacent support in response to a detonation of the charge 17.

Interposed between the studs 18 and 19 and the charge 17 are the waddings 22 and 23 for preventing the gases released from the detonation of the charge 17 from by-passing the studs 18 and 19.

An electrically-actuable detonating structure is carried by the tube for exploding the charge 17, to thereby cause the prongs to be driven into the supports 11 and 12. As clearly illustrated in Figures 4 and 5, the detonating structure includes a firing pin 25 which is supported in a transversely extending bore 26 provided in the tube 15. One end of the firing pin 25 extends into the charge 17, while the other end thereof terminates exteriorly of the tube 15 and has secured thereto wires 27 which are adapted to be selectively connected to a source of electrical energy to detonate the charge 17.

Circumposed about the tube 15 intermediate the ends thereof is a reinforcing sleeve 30 which has its respective ends projecting substantial distances beyond the outer ends of the cylindrical stud bodies, and which is detachably secured to the tube 15 to prevent the latter from rupturing when the explosive charge 17 is exploded. As clearly shown in Figures 2, 3 and 5, the reinforcing sleeve includes a pair of sleeve sections 31 and 32 arranged in face-to-face relation with respect to each other. The sleeve sections 31 and 32 are longitudinally cut to form complementary intermeshing hinges 33 and 34 and 35 along the respective pairs of facing side edges thereof. Interconnected between the hinge leaves of one pair of facing side edges of the sleeve sections 31 and 32 is a hinge pin 36 which mounts the sleeve

sections 31 and 32 for pivotal movement relative to each other. Traversing the hinge leaves of the other pair of facing side edges of the sleeve sections 31 and 32 is a removable pin 37 for detachably securing the sleeve sections together. As clearly shown in Figure 4, the inner periphery of the sleeve 30 is provided with a seat 38 for receiving the projecting end of the firing pin 26. The sleeve section 31 is further provided with an aperture 39 having one end terminating in the outer periphery thereof and having the other end terminating in the seat 38 for the extension therethrough of the wires 27 of the detonating structure.

As illustrated in phantom in Figure 1, any piece of electrical equipment, such as an outlet box 50, may be dependingly supported from the tube 15 after the removal of the reinforcing sleeve 30.

In actual use, the reinforcing sleeve is circumposed about the tube 15 with the wires 27 projecting exteriorly thereof. Upon attaching the wires to a source of electrical energy, the charge 17 is exploded, whereupon the prongs 21 of the projectile-like studs 18 and 19 are driven into the supports 11 and 12 and permanently and firmly secure the hanger bar 10 to the supports. The hanger bar of the present invention can be mounted between joists or trusses in buildings which are being rewired, where conventional hanger bars are not practical. The hanger bar 10 facilitates a solid mounting which cannot be obtained by mounting boxes or hangers on lath, plasterboard, masonite, and similar supports.

Although only one embodiment of the hanger bar of the present invention has been described, it is readily apparent that numerous modifications can be made without departing from the spirit of the invention as set forth in the appended claims.

What I claim is:

1. A hanger bar for attachment between a pair of spaced supports comprising an open-ended hollow tube adapted to be extended between said supports, an explosive charge disposed within said tube intermediate the ends thereof and supported therebetween, a pair of projectile-like studs normally arranged in back-to-back spaced relation with respect to each other in the medial portion of said tube on opposite sides of said charge, said studs including cylindrical bodies and prongs on the outer ends of the bodies, each of said studs being driven from its normal position toward the adjacent open end of said tube for engagement of the prongs with the adjacent support in response to the detonation of said charge, electrically actuatable detonating means carried by said tube for exploding said charge, and a reinforcing sleeve circumposed about said tube intermediate the ends thereof and detachably secured thereto, said sleeve having its opposite ends extending a substantial distance beyond the outer ends of said bodies in the normal position of the studs.

2. A hanger bar for attachment between a pair of spaced supports comprising an open-ended hollow tube adapted to be extended between said supports, an explosive charge disposed within said tube intermediate the ends thereof and supported therebetween, a pair of projectile-like studs normally arranged in back-to-back spaced relation with respect to each other in the medial portion of said tube on opposite sides of said charge, said studs including cylindrical bodies and prongs on the outer ends of the bodies, each of said studs being driven from its normal position

toward the adjacent open end of said tube for engagement of the prongs with the adjacent support in response to the detonation of said charge, electrically actuatable detonating means carried by said tube for exploding said charge, and a reinforcing sleeve circumposed about said tube intermediate the ends thereof and detachably secured thereto, said sleeve having its opposite ends extending a substantial distance beyond the outer ends of said bodies in the normal position of the studs, said detonating means including wires adapted to be electrically connected to a source of electrical energy, and a firing pin electrically connected to said wires and having one end extending through a bore provided in said tube and having the other end received in a seat provided in the inner periphery of said reinforcing sleeve, there being an aperture provided in said reinforcing sleeve having one end terminating in the other periphery thereof and having the other end terminating in said seat for the extension therethrough of said wires.

3. A hanger bar for attachment between a pair of spaced supports comprising an open-ended hollow tube adapted to be extended between said supports, an explosive charge disposed within said tube intermediate the ends thereof and supported therebetween, a pair of projectile-like studs normally arranged in back-to-back spaced relation with respect to each other in the medial portion of said tube on opposite sides of said charge, said studs including cylindrical bodies and prongs on the outer ends of the bodies, each of said studs being driven from its normal position toward the adjacent open end of said tube for engagement of the prongs with the adjacent support in response to the detonation of said charge, electrically actuatable detonating means carried by said tube for exploding said charge, and a reinforcing sleeve circumposed about said tube intermediate the ends thereof and detachably secured thereto, said sleeve having its opposite ends extending a substantial distance beyond the outer ends of said bodies in the normal position of the studs, said reinforcing sleeve comprising a pair of sleeve sections arranged in face-to-face relation with respect to each other, said sleeve sections being longitudinally and transversely cut to form complementary intermeshing hinge leaves along the respective pairs of facing side edges thereof, means interconnected between the hinge leaves of one pair of facing side edges of said sleeve sections for mounting said sleeve sections for pivotal movement relative to each other, and a removable pin traversing the hinge leaves of the other pair of facing side edges of said sleeve sections for detachably securing said sleeve sections together.

JOSEPH P. FRANZ.
